TOY

Frederick J. Ebeling, Staunton, Va.

Application November 23, 1943, Serial No. 511,445

7 Claims. (Cl. 46—201)

My invention relates to toys and more particularly to a wheeled toy.

The principal object of the invention is to provide a wheeled toy having a number of separate parts which may be easily assembled in a variety of ways by a young child.

Another object of the invention is to provide a toy having a plurality of wheeled units of such character that they may be either used separately or easily combined into a single operative device.

A further object of the invention is to provide a simple and inexpensive wheeled toy which is made entirely of wood and has a plurality of movable parts.

A primary feature of the invention consists in providing a toy with a plurality of independent units each having a rigid member and wheels arranged on opposite sides thereof in frictional engagement with the wheels of the other unit, some of the wheels on one unit being arranged in overlapping relation with the rigid member of the other unit for limiting lateral movement of the units.

Another feature of the invention consists in providing a toy with a plurality of pairs of wheels and a member revoluble about an axis substantially normal to the axes of the wheels which is frictionally engageable with both wheels of one of the pairs.

Other and more specific features of the invention, residing in advantageous forms, combinations and relations of parts, will hereinafter appear and be pointed out in the claims.

In the drawings, illustrating a preferred embodiment of the invention,

Figure 1 is a plan view of the toy.

Figure 2 is a side elevational view of the toy with the turret omitted.

Figure 3 is an end view of the toy as viewed from the right side of Figure 1.

Figure 4 is a side elevational view of the upper unit of the toy and the turret.

Figures 5 to 8, inclusive, are diagrammatic views illustrating some of the ways in which the various parts of the toy may be assembled and used.

In the particular embodiment of the invention illustrated in the drawings, the toy is formed of two wheeled units but it is, of course, to be appreciated that a greater number of wheeled units may be employed if desired.

The main unit 1 comprises a plurality of pairs of wheels 2 which may advantageously be connected by a rigid block-like member 3 which is interposed between the wheels of each pair.

Each pair of wheels is freely rotatable and preferably mounted on the ends of axles which extend through suitable openings in the connecting member 3. The opening in the wheels into which the outer ends of the axles extend are of substantially the same diameter as the axles so that the wheels will be frictionally held thereon while the openings in the connecting member through which the axles extend are of greater diameter than the axles so that the latter are freely rotatable.

The upper or auxiliary unit 5 of the toy is of similar construction to the main unit 1 but instead of having three pairs of wheels it preferably has but two pairs. Like the main unit, the auxiliary unit comprises a plurality of pairs of wheels 6 frictionally held on the outer end of axles 7 extending through openings in a rigid connecting member 8, the diameter of these openings being substantially larger than that of the axles so that the axles are freely rotatable therein.

The arrangement and diameter of the wheels of the two units is such that, when the upper unit 25 is placed on the lower unit, the wheels 6 of the upper unit frictionally engage the wheels 2 of the lower unit and the connecting member 8 of the upper unit will be supported by the axles 7 in spaced relation to the connecting member 3 of the lower unit. It will thus be apparent that, when the lower unit is pulled along the floor and the wheels 2 are caused to rotate, the wheels 6 of the upper unit will also be caused to rotate but in the opposite direction. The wheels of at least one of the units are of such diameter that they will be arranged in overlapping relation to the rigid member of the other unit so as to limit relative lateral movement or shifting of the two units.

40 Removably mounted within an opening 9 in the rigid member 8 of the upper unit is an upwardly extending spindle or the like 10 which affords a pivotal mounting for a turret-like member 11. The spindle extends within an opening in the member 11 which is of substantially greater diameter than the spindle so that the turret is freely rotatable thereon and may angle slightly with respect thereto. The member 11 may be formed to simulate the appearance of a turret on a tank and to carry out this effect it may be advantageously formed with an opening in its side into which a rod or the like 12, representing a gun, may be inserted.

The under side of the turret is formed with an inclined portion 13 which is frictionally en-

gageable with both wheels of one of the pairs of wheels of the upper unit 5. This incline is such that, when the turret is caused to rotate in one direction, it will move from engagement with one of the wheels with which it is intended to coact and by virtue of its coaction with the other wheel the turret is caused to move upwardly on the spindle 10.

The inclined surface 13 will tend to cause the turret to normally occupy the position shown in Figure 4 or a position at 180° with respect thereto. However, unevenness in the floor or ground along which the toy is pulled and perhaps also inaccurately made parts of the toy itself will tend to cause the turret to wobble and rotate slightly on its spindle. This tendency of the turret is accentuated by the imbalance imparted to the turret by the rod 12. Whenever because of these factors the turret is caused to rotate sufficiently, as indicated in full lines in Figure 1, that the frictional force exerted thereon by one of its supporting wheels is substantially greater than the frictional force exerted thereon by the other supporting wheel, the turret will then rotate approximately 180° into the dotted line position indicated in Figure 1. The turret will remain in this position until the frictional forces which are exerted by its two supporting wheels on its inclined under surface are sufficiently out of balance to cause the turret to rotate again.

It is apparent that the construction of the wheeled units of the toy is such that they may be assembled in relations other than that shown in Figures 1 to 3, inclusive. For example, the upper unit instead of being arranged centrally with respect to the lower unit may be arranged as shown in Figure 5 or the two units may be inverted as shown in Figure 6 so that what has been described as the upper unit becomes the lower unit and what has been described as the lower unit becomes the upper unit. The turret 11 can, of course, still be used when the units are thus assembled by merely providing the connecting member 3 of the upper unit with a suitable opening into which the spindle 10 may be inserted.

Not only are the two units capable of being conjointly used in various ways but each unit is capable of separate use if that be desired. Thus the upper unit with the turret may be used independently of the lower unit, as shown in Figure 4. Moreover, other removable parts are capable of being easily associated with either one or the other of the two units so that their separate use might be rendered more appealing and interesting to a child. For example, the connecting member 3 of the main unit 1 can be provided with apertures 14 to receive pegs or the like for supporting elements 15 which, if desired, may simulate turrets. Likewise the auxiliary unit 5 may be provided with one or more apertures, such as indicated at 16, to receive a peg on which element 17 simulating an anti-aircraft gun might be mounted, as shown in Figure 8. It will, of course, be appreciated that members of any desired form may be made available for removable association with either of the wheeled units in place of those members shown in Figures 7 and 8 of the drawings.

From the foregoing, it will be seen that a simple and inexpensive toy is provided consisting of a plurality of wheeled units which may be easily assembled by even the youngest child for conjoint use or which may be readily disas-

sembled for separate use. Various changes and modifications may be made in the details of the embodiment of the invention herein illustrated without departing from the spirit and scope of the invention as defined in the appended claims.

5. What I claim is:

1. A wheeled toy including two superposed unconnected units each having a rigid member provided with a plurality of wheels on opposite sides thereof, the wheels of each unit being in frictional engagement with the wheels of the other unit and the wheels of one of said units being arranged to overlap opposite sides of the rigid member of the other unit for preventing relative lateral movement of said units.
10. 2. A wheeled toy including two superposed unconnected units each having a rigid member, axles extending from opposite sides of each of said rigid members and wheels carried on the outer ends of said axles, the wheels of each unit being in frictional engagement with the wheels of the other unit and the wheels of one of said units being arranged in overlapping relation to the opposite sides of the rigid member of the other unit for limiting relative lateral movement of said units.
15. 3. A wheeled toy including two superposed units each having a plurality of pairs of wheels in frictional engagement with the wheels of the other unit, and a member rotatably mounted on the upper one of said units for movement about an axis substantially normal to the axes of said wheels, the under side of said rotatable member being frictionally engageable with both wheels
20. 35. of one of the pairs of wheels of said upper unit, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.
25. 4. A wheeled toy including two superposed units each having a plurality of pairs of wheels in frictional engagement with the wheels of the other unit, a shaft extending upwardly from the upper one of said units, and a rotatable member loosely encircling said shaft engageable with both wheels of one of the pairs of wheels of said upper unit, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.
30. 5. A wheeled toy comprising a plurality of pairs of supporting wheels, a connecting member for said wheels interposed between the wheels of each pair, and a rigid member rotatably mounted on said connecting member for movement about an axis substantially normal to the axes of said wheels, said rotatable member being frictionally engageable with both wheels of one of said pairs of wheels and being adapted to wobble indiscriminately with respect to its axis of rotation so that the frictional force exerted thereon by one of the wheels of the last named pair is sufficiently greater than the frictional force exerted thereon by the other one of the wheels of said last named pair to cause partial rotation of the member upon normal travel of the toy.
35. 6. A wheeled toy including two superposed units each having a plurality of pairs of wheels in frictional engagement with the wheels of the other unit, a shaft extending upwardly from the upper one of said units, and a rotatable member loosely encircling said shaft engageable with both wheels of one of the pairs of wheels of said upper unit, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.
40. 7. A wheeled toy including two superposed units each having a plurality of pairs of wheels in frictional engagement with the wheels of the other unit, a shaft extending upwardly from the upper one of said units, and a rotatable member loosely encircling said shaft engageable with both wheels of one of the pairs of wheels of said upper unit, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.
45. 8. A wheeled toy including two superposed units each having a plurality of pairs of wheels in frictional engagement with the wheels of the other unit, a shaft extending upwardly from the upper one of said units, and a rotatable member loosely encircling said shaft engageable with both wheels of one of the pairs of wheels of said upper unit, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.
50. 9. A wheeled toy including two superposed units each having a plurality of pairs of wheels in frictional engagement with the wheels of the other unit, a shaft extending upwardly from the upper one of said units, and a rotatable member loosely encircling said shaft engageable with both wheels of one of the pairs of wheels of said upper unit, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.
55. 10. A wheeled toy including two superposed units each having a plurality of pairs of wheels in frictional engagement with the wheels of the other unit, a shaft extending upwardly from the upper one of said units, and a rotatable member loosely encircling said shaft engageable with both wheels of one of the pairs of wheels of said upper unit, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.
60. 11. A wheeled toy comprising a plurality of pairs of supporting wheels, a connecting member for said wheels interposed between the wheels of each pair, and a rigid member rotatably mounted on said connecting member for movement about an axis substantially normal to the axes of said wheels, said rotatable member being frictionally engageable with both wheels of one of said pairs of wheels and being adapted to wobble indiscriminately with respect to its axis of rotation so that the frictional force exerted thereon by one of the wheels of the last named pair is sufficiently greater than the frictional force exerted thereon by the other one of the wheels of said last named pair to cause partial rotation of the member upon normal travel of the toy.
65. 12. A wheeled toy including two superposed units each having a plurality of pairs of wheels in frictional engagement with the wheels of the other unit, a shaft extending upwardly from the upper one of said units, and a rotatable member loosely encircling said shaft engageable with both wheels of one of the pairs of wheels of said upper unit, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.
70. 13. A wheeled toy including two superposed units each having a plurality of pairs of wheels in frictional engagement with the wheels of the other unit, a shaft extending upwardly from the upper one of said units, and a rotatable member loosely encircling said shaft engageable with both wheels of one of the pairs of wheels of said upper unit, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.

6. A wheeled toy comprising a plurality of pairs of supporting wheels, a connecting member for said wheels interposed between the wheels of each pair, and a rigid member rotatably mounted on said connecting member for movement about an axis substantially normal to the axes of said wheels, the under side of said rotatable member being inclined and being frictionally engageable with both of the wheels of one of said pairs of wheels, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.

7. A wheeled toy comprising a plurality of pairs of supporting wheels, a connecting mem- 20

ber for said wheels interposed between the wheels of each pair, a spindle extending upwardly from said connecting member, and a revolvable member loosely encircling said spindle and having an inclined portion on its under side, said inclined portion being frictionally engageable with both of the wheels of one of said pairs of wheels and being movable from engagement with one of said wheels upon rotation of the revolvable member, said member being adapted to wobble indiscriminately with respect to its axis of rotation so that the frictional force exerted thereon by one of the wheels of the last named pair is sufficiently greater than the frictional force exerted thereon by the other one of the wheels of the last named pair to cause partial rotation of the member upon normal travel of the toy.

FREDERICK J. EBELING.
